UNITED STATES PATENT OFFICE.

HENRY F. HENDRICKS AND JAMES H. DENTON, OF PHILADELPHIA, PENNSYLVANIA, ASSIGNORS TO JAMES H. BATES, OF SOMERSET, KENTUCKY.

TROLLEY-GUARD.

SPECIFICATION forming part of Letters Patent No. 597,282, dated January 11, 1898.

Application filed September 12, 1896. Serial No. 605,586. (No model.)

To all whom it may concern:

Be it known that we, HENRY F. HENDRICKS and JAMES H. DENTON, citizens of the United States, residing at Philadelphia, in the county 5 of Philadelphia and State of Pennsylvania, have invented certain new and useful Improvements in Trolley-Guards, of which the following is a specification.

This invention relates to a new and useful 10 improvement in trolley-guards, and has for its object to provide a device which may be readily attached to the fork of an ordinary trolley-pole, and when so attached will overcome the liability which has heretofore existed of the trolley-wheel leaving the feed-wire over which it travels, and especially when 15 said wheel is passing a crossing where two feed-wires intersect each other at an angle.

With these ends in view this invention consists 20 in the details of construction and combination of elements hereinafter set forth, and then specifically designated by the claims.

In order that those skilled in the art to which this invention appertains may understand 25 how to make and use the same, its construction and operation will now be described, referring to the accompanying drawings, forming a part of this specification, in which—

Figure 1 is a side elevation of the upper 30 portion of a trolley-fork, showing this improvement attached thereto and illustrating its relative position to the feed-wire and crossing; and Fig. 2 a plan view of the trolley-fork and crossing, showing the star-wheels in section.

Referring to the drawings in detail, A represents the trolley-fork, which may be of any ordinary construction, and B the trolley-wheel, journaled therebetween in the usual 40 manner. To this fork is secured, by means of the journal-bolt C, two brackets D, which may be provided with offsets E of such shape as to fit on edge of each of the prongs of the fork, so as to resist the downward strain 45 brought to bear upon the brackets when the trolley is traveling upon its feed-wire. Between these brackets is journaled a roll F, and upon the outside of each of the brackets is also journaled a star-wheel G, the bolt H 50 serving to journal both the roll and the star-

wheels. From this it will be seen that as a trolley provided with this improvement travels along its feed-wire the star-wheels will perform no function, but rest idly until coming into contact with the crossing, as shown at 55 I, when as the trolley-wheel passes under said crossing the star-wheels will engage with the inclined leaders J, that lie at right angles to the feed-wire upon which the trolley is traveling, and act as gear-wheels meshing with a 60 rack-bar, thereby preventing the trolley-wheel from jumping off its feed-wire when passing from one leader to the other.

In practice it will be found that the star-wheels will not only serve to hold the trolley 65 in its proper relative position to the feed-wire when passing a crossing, but will likewise prevent said wheel from jumping its wire when turning curves, and by the assistance of the roll F will also prevent the trolley- 70 wheel from leaving its feed-wire when not turning curves or passing crossings, since the roll forms a secondary trolley and is of less diameter in cross-section at its center than at its ends, so that should the trolley leave 75 its wire the roll F will come in contact with said wire and tend to again center the trolley under the wire, and this is further facilitated by the star-wheels in that they serve to prevent the roll F from passing beyond certain 80 limits sidewise.

The star-wheels are here shown as having openings K in each of their points for the purpose of lightening the same; but it is obvious that these wheels might be made of 85 sheet metal, and it is also obvious that the roll F and brackets may be omitted and the star-wheels journaled upon the outside of the fork upon the bolt C, or a bridge may be substituted for the roll F, which would make the 90 completed device of less weight.

One of the advantages of this improvement is that when the trolley passes under an arch or bridge where the feed-wire is secured to a housing and is of less height from the road-bed of the car than is usually the case at other points of the line, thus depressing the trolley-arm, the star-wheels will be swung downward relative to the point of contact between the feed-wire and the trolley-wheel, 95 100

thereby carrying them out of action, which will prevent them from coming in contact with said housing.

Other slight modifications might be made in the design here shown without departing from the spirit of this invention, and it is therefore not desired to limit said improvement to the exact construction here shown and described.

Having thus fully described this invention, what is claimed as new and useful is—

1. In a trolley, a fork, a bolt secured thereto, a trolley-wheel journaled on the bolt, diverging brackets secured to the bolt at an angle to the fork, a second bolt connecting the brackets, a secondary trolley-wheel journaled on the second bolt between the brackets and star-wheels journaled on the second bolt outside the brackets, as and for the purpose described.

2. In a trolley, a fork, a bolt secured thereto, a trolley-wheel journaled on the bolt, diverging brackets secured to the bolt at an angle to the fork, a second bolt connecting the

brackets, a secondary trolley-wheel journaled on the second bolt between the brackets, star-wheels journaled on the second bolt outside the brackets and offsets on the brackets adapted to engage the fork, as and for the purpose described.

3. In a trolley a fork, a trolley-wheel journaled therein, brackets rigidly secured to said fork at an angle thereto and a secondary trolley-wheel and a star or guide wheel journaled in the brackets whereby the secondary trolley-wheel is normally in contact with the trolley-wire but when the trolley-wire becomes lower the secondary trolley-wheel is thrown out of contact, as and for the purpose described.

In testimony whereof we have hereunto affixed our signatures in the presence of two subscribing witnesses.

HENRY F. HENDRICKS.
JAMES H. DENTON.
